UNITED STATES PATENT OFFICE.

JESSE A. DUBBS, OF PITTSBURG, PENNSYLVANIA.

TREATING OIL.

No. 890,762.

Specification of Letters Patent.

Patented June 16, 1908.

Application filed November 9, 1905. Serial No. 286,472.

To all whom it may concern:

Be it known that I, JESSE A. DUBBS, residing at Pittsburg, in the county of Allegheny and State of Pennsylvania, a citizen of the United States, have invented or discovered certain new and useful Improvements in Treating Oil, of which improvements the following is a specification.

It is characteristic of some crude petroleum oils that water is mingled or combined therewith in such manner as to render it impossible to separate the water and oil, as is necessary for refining, by any of the methods known in the art. While not stating it to be a fact, it is thought that by reason of the presence of some substance an emulsion is formed by the water and oil, the water appearing in an extremely fine divided state. It has been attempted to separate the oil and water by heat and distillation, but such attempts have been unsuccessful.

In the accompanying drawing forming a part of this specification is shown in sectional elevation a form of apparatus adapted to the practice of my invention.

I have found that by subjecting this crude oil to a high heat while held from vaporization, and allowing the material to cool, that the water will segregate and settle down through the oil and can be drawn off in the usual manner.

In the practice of my invention the crude oil is run into a suitable receptacle 1 in which it can be subjected to the required heat as by a steam coil 2, and at the same time prevented from material vaporization. In this receptacle the crude oil is subjected to a temperature above the vaporizing temperature of the oil and water, *i. e.*, to a temperature at which the vaporization of the lightest constituent will be at the rate of about five per cent. or one-twentieth of a cubic foot per hour at atmospheric pressure per square foot of exposed area. In general this temperature is found to be approximately equal to 250 or 300° Fahrenheit. As oils vaporize at different temperatures dependent upon the presence and proportion of the benzin or other lighter hydrocarbon constituent in the oil, the vaporizing temperature herein referred to is that temperature at which the vaporiza-

tion will be free and full at atmospheric temperature, or at a rate of 5 per cent. per hour per square foot of exposed area. The coil 2 is connected in an operation to a suitable steam generator, and also to a superheater when necessary. After the oil has been heated as above specified, vaporization being prevented by the pressure generated in the receptacle by the heat, the contents of the receptacle are allowed to cool below a temperature at which the lightest constituents will vaporize freely and preferably to atmospheric temperature. The oil after passing below vaporizing temperature is preferably run into another receptacle where it can be free from agitation to afford opportunity for the gravity separation of the water from the oil.

While the receptacle or chamber in which the oil is heated may be filled with oil so that there will be no separation of vapors and liquids when heated, it is found that more heat units and a longer time are required to bring the oil to the proper temperature under such conditions, than if a small vacancy is left in the vessel to permit of some expansion of the liquids while being heated.

In order to prevent any injury to the receptacle by excessive pressure, means are provided as the safety valve 3 to relieve pressure when it approaches a dangerous point.

I claim herein as my invention:

As an improvement in the art of separating oil and water the method herein described which consists in heating the mixed oil and water at a temperature above that at which the vaporization would be at the rate of about one-twentieth of a cubic foot per square foot of surface area per hour at atmospheric pressure, preventing any substantial vaporization and allowing the oil and water to cool below vaporizing temperature, whereby the oil and water are allowed to stratify in accordance with their relative specific gravities.

In testimony whereof I have hereunto set my hand.

JESSE A. DUBBS.
